(57) **CLAIM**

The ornamental design for a vehicle wheel, as shown and described.

DESCRIPTION

FIG. 1 is a frontside perspective view of the vehicle wheel;
FIG. 2 is a rearside perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof, and,
FIG. 8 is a bottom view thereof.

The broken lines shown in the drawings depict portions of the vehicle wheel that form no part of the claimed design.
